UNITED STATES PATENT OFFICE.

AUTHUR E. FOLSON, OF WINCHEON, MASSACHUSETTS, ASSIGNOR TO WILLIAM H. WHITNEY, OF WINCHEON, MASSACHUSETTS.

WOOD-PLANING MACHINE.

1,212,618.

Specification of Letters Patent. Patented Jan. 16, 1917.

Application filed December 23, 1913. Serial No. 808,187.

To all whom it may concern:

Be it known that I, ARTHUR E. FOLSON, a citizen of the United States, residing at Winchendon, county of Worcester, and State of Massachusetts, have invented an Improvement in Wood-Planing Machines, of which the following description, in connection with the accompanying drawings, is a specification, like letters on the drawings representing like parts.

The invention to be hereinafter described relates to surface planers, and more particularly to those surface planers in which the cutter cylinder or cylinders are each driven directly from a motor.

There are two types of wood planers in common use at the present time, namely, the single surfacer and the double surfacer. The single surfacer finishes but one surface of a board or piece of timber while a double surfacer finishes both sides of the work. A double surfacer has two cutter cylinders, the upper cylinder usually being fixed and the lower cylinder being adjustable toward and from the upper cylinder to accommodate work of different thicknesses and to vary the depth of cut; and in order that work of uniform thickness may be produced, the two cylinders should remain parallel throughout all positions of adjustment.

The present invention contemplates the provision of direct motor drive for the cutter cylinder or cylinders and appropriate adjusting means, all of which will best be understood from the following description and accompanying drawings of the preferred embodiment of the invention, in which:

Figure 1 is a general view of a double surface planer embodying the present invention; Fig. 2 is a perspective view of one of the side frames and some of the parts carried thereby; Fig. 3 is an enlarged detail with parts in section showing more particularly the manner of supporting the lower cutter cylinder and motor; Fig. 4 is a section on the line 4-4 of Fig. 3; and Fig. 5 is an end view of one of the motors.

The machine shown in Fig. 1 comprises side frames 1 and 2 connected by braces 3, a work supporting table 4 and a series of rolls 5 to feed the work. The lower cutter cylinder 6 carries knives 7 and is provided with an extension shaft 8 which is journaled in suitable bearings, such as boxes 9. As

shown in the illustrated form of the invention, an upper cutter cylinder similar to the cylinder 6 may be mounted on a shaft having journals carried by the upper part of the side frames, and said shaft may be connected by a train of gearing 10, 11 with the feed rolls 5, as indicated in Fig. 1.

The table 4 is adjusted vertically to vary the distance between the cylinders and the feed rolls, by two pairs of wedges, the lower wedges 12, Figs. 1, 2 and 3, being preferably movable longitudinally of the machine and the upper wedges 13 being constrained to vertical movement by suitable ways 14. The boxes carrying the lower cutter cylinder are secured to a slide 15 by bolts 16, Fig. 3 and said slide 15 is held in a way on a slide frame 17 which is carried by the upper wedges 13 so as to move with the table. By this construction the cylinder carrying slide 15 may be easily removed from the machine for convenience in manipulating the cutters. In order that the cylinder 6 may be capable of adjustment independently of the table 4 to vary the depth of cut, a pair of small wedges 18 are preferably interposed between the wedges 13 and the slide frame 17, the wedges 18 being mounted to slide in suitable ways 19 in which they may be moved by a worm and screw 20 or other suitable means.

The angular relation of the cylinder and the table is under control of a wedge 24 (Fig. 4) seated in a slot 25 in the slide frame 17 below the slide 15. The bottom of the slot is cut on an angle corresponding to the angle of the wedge 24 and the upper surface of the wedge is horizontal. The wedge is adjusted by a nut 26 on a stud 27 projecting from the wedge, which extends outside the slide frame.

The lower cylinder is driven by an electric motor 28 connected to the cutter cylinder shaft 8 by a flexible coupling which, in order to facilitate the removal of the slide 15, is preferably disengaged by longitudinal movement of the slide. A convenient coupling of this character is formed by a collar 29 on the motor shaft 30 and a collar 31 on the cutter cylinder shaft 8, driving connections between the collars being secured by a floating disk 32 having a tongue 33 on each side at right angles to each other, each of which engages a complementary slot in the collars 29 and 31 respectively. In order to secure the best qual.

ity of work and efficiency in operation of the machine, it is desirable that the motor and cutter cylinder shafts shall be in proper alinement or substantially so, and to this end provision is made to permit adjustment of the motor to bring the shaft thereof into substantial alinement with the cutter cylinder shaft by mounting the motor on movable supporting devices. The motor 28 is preferably secured to a plate 34 by bolts 35. This plate 34 rests on a bracket 36 upon which it can be moved longitudinally of the machine by loosening one and tightening the other of a pair of set screws 37, Figs. 3 and 5. The set screws pass through ears 38 depending from each side of the plate 34 so that the points of the screws bear against the bracket 36, as indicated in Fig. 5. The plate and bracket are provided with a tongue and groove connection 39 to guide the movement of the plate and said parts may be rigidly held in adjusted relation by suitable means, such as the bolts 40 passing through slots 41 in the bracket. The bracket 36 is itself mounted for vertical adjustment on an apron 42, preferably attached to the end of the slide frame 17 by bolts 43, and is held against the apron and secured in adjusted position by suitable means, such as the bolts 44 which pass through slots 45 in the bracket, as indicated in Fig. 3. Vertical movement of the bracket is secured by a screw 46 threaded into a lug 47, Fig. 3, on the apron, the construction being such that the end of the screw 46 engages the bracket and serves to impart movement thereto when the holding devices or bolts 44 are released. A check nut 48 holds the screw 46 against dis- placement. The lower end of the apron 42 is supported in vertical ways 49 on the side frame 1 which permit the motor and its supporting members to move freely in a vertical plane as the cutter cylinder is adjusted by means of the wedges 12, 13, or 18. The bracket 36 also carries an adjustable stop 50, Fig. 3, which engages the end of the cutter cylinder slide 15 and so positions the cylinder laterally of the machine. In the double surfacer the upper cutter cylinder is driven by a separate motor 55 mounted on a plate 34' which is in turn mounted on a bracket 36'. The supports and adjustments for the motor and upper cutter cylinder may be substantially the same as those for the lower cutter cylinder and motor, except that as the upper cylinder may have no vertical movement, the bracket 36' may be mounted directly on the side frame 2 in the same way that the bracket 36 is mounted on the apron 42. The construction described in connection with the lower cutter cylinder provides a direct connected motor cylinder in which

the motor and the cylinder are independently adjustable and means for retaining the members in adjusted relation without interfering with the movement of the cylinder when its position is changed in accordance with the character of the work.

It is to be understood that the invention is not limited to the exact construction and arrangement of parts herein set forth, but that it may be varied within the skill of a mechanic without departing from the scope of the invention as defined by the appended claims.

What is claimed is:

1. In a machine of the character described, the combination of a table and a cutter cylinder, work-engaging means opposed thereto, means for effecting simultaneous adjustment of the table and cutter cylinder toward and from the opposed work-engaging means for varying thickness of the work, means for effecting adjustment of the cutter relative to the table to vary the depth of cut, a self-contained motor movable with the table and cutter as they are adjusted for thickness of work, and connections between the motor and cutter to effect movement of the motor with the cutter as the latter is moved relatively to the table to vary the depth of cut.

2. In a machine of the character described, the combination of a table and a cutter cylinder, work-engaging means opposed thereto, means for effecting simultaneous adjustment of the table and cutter cylinder toward and from the opposed work-engaging means for varying thickness of the work, means for effecting adjustment of the cutter relative to the table to vary the depth of cut, a self-contained motor movable with the table and cutter as they are adjusted for thickness of work, connections between the motor and cutter to effect movement of the motor with the cutter as the latter is moved relatively to the table to vary the depth of cut, and means for adjusting the motor in a plurality of directions independently of the cutter cylinder.

3. In a machine of the character described, the combination of a cutter shaft and cutter, a table over which the work is fed, journals for supporting the ends of the cutter shaft, means for independently adjusting the journals with respect to the table to vary the depth of cut at either side of the table, a self-contained motor and its shaft, a flexible coupling operatively connecting the motor shaft and cutter shaft end to end and permitting adjustment of the cutter shaft while said shafts are operatively connected, and means for adjusting the motor and its shaft in a plurality of directions independently of the cutter shaft.

4. In a machine of the character de-

- scribed, the combination of a table and a cutter cylinder, work-feeding means opposed thereto, means for adjusting the table and cutter cylinder together toward and from the plane of the work-feeding means for variations in thickness of work, means for adjusting the cutter and table relatively for varying the depth of cut, means for separately adjusting the end of the cutter cylinder for varying the plane of cut, a self-contained motor mounted for movement with the table and cutter cylinder as they are adjusted for variations in thickness of the work, and for movement with the cutter cylinder independently of the table as the cutter cylinder is moved relatively to the table to vary the depth of cut, and means for adjusting the motor independently of the cutter cylinder.
5. In a machine of the character described, the combination of a main frame, a slide frame vertically adjustable on the main frame, a cutter cylinder and shaft carried by the vertically adjustable slide frame, an apron depending from the slide frame and secured thereto, a bracket adjustably secured to the depending apron, a plate adjustably mounted on the bracket, a self-contained motor and shaft secured to the
- plate for adjustment therewith relative to 30 the bracket, and also adjustable with the bracket, a flexible coupling connecting the motor shaft and cutter cylinder shaft end to end, and means for adjusting the cutter cylinder relative to the slide frame.
6. In a machine of the character described, the combination of a frame, a table over which the material to be treated is fed, a cutter cylinder and shaft mounted in the frame, means for relatively adjusting the 40 cutter cylinder shaft and table, a bracket, means for adjusting the bracket relative to the cutter cylinder, a plate mounted on the bracket, a self-contained motor and shaft mounted on the plate, means for adjusting 45 the plate and self-contained motor on the bracket, and a flexible coupling connecting the motor shaft and cutter shaft end to end and permitting relative adjustment of said shafts.
- 50 In testimony whereof, I have signed my name to this specification, in the presence of two subscribing witnesses.
